UNITED STATES PATENT OFFICE.

DANIEL E. SPEICHER AND ELROY C. FAUST, OF URBANA, INDIANA.

FEED TROUGH.

Application filed November 2, 1923. Serial No. 672,378.

To all whom it may concern:

Be it known that we, DANIEL E. SPEICHER and ELROY C. FAUST, citizens of the United States, residing at Urbana, in the county of 5 Wabash and State of Indiana, have invented certain new and useful Improvements in Feed Troughs, of which the following is a specification.

This invention relates to a feed trough, 10 designed primarily for use for the feeding of chickens, but it is to be understood that a trough in accordance with this invention can be employed for any purpose wherein it is found applicable, and the invention has for 15 its object to provide, in a manner as herein-after set forth, a feed trough comprising a container or body portion and an apertured cover or lid for the container, and with the container and cover having coacting means 20 for detachably securing the cover in closure position with respect to the container and in such manner as to prevent the cover from being accidentally shifted from off the container.

25 A further object of the invention is to provide, in a manner as herein-after set forth, a feed trough comprising a container and a cover or lid therefor, and with the cover formed with two sets of spaced openings to 30 enable the fowls to have access to the food in the container and with the portions of the cover surrounding each opening upset in a semi-circular manner to prevent a wall of an opening injuring the fowls when feeding, as well as acting as a means to reinforce 35 the cover to increase the life thereof.

40 A further object of the invention is to provide, in a manner as herein-after set forth, a feed trough comprising a container and a cover or lid therefor, and with the container and cover reinforced at the corners thereof, thereby increasing the life of the trough.

45 Further objects of the invention are to provide a feed trough, in a manner as herein-after set forth, which is simple in its construction and arrangement, strong, durable, thoroughly efficient in its use, readily assembled and inexpensive to manufacture.

50 With the foregoing and other objects in view, the invention consists of the novel construction, combination and arrangement of

parts, as hereinafter more specifically described and illustrated in the accompanying drawings, wherein is shown an embodiment of the invention, but it is to be understood 55 that changes, variations and modifications can be resorted to which come within the scope of the claims hereunto appended.

In the drawings wherein like reference characters denote corresponding parts 60 throughout the several views:—

Figure 1 is a top plan view of a feed trough in accordance with this invention.

Figure 2 is a side elevation.

Figure 3 is a plan of the container or body 65 portion with the cover or lid removed.

Figure 4 is a longitudinal sectional view of the trough.

Figure 5 is a section on line 5—5, Figure 70 2.

A feed trough in accordance with this invention is constructed from sheet metal of suitable gauge and comprises a feed container and a cover or lid therefor, and with means for detachably securing the cover or 75 lid to the container. The container, as well as the cover or lid, is formed from one sheet of material, preferably stamped to the shape as illustrated.

The container or body portion of the 80 trough is substantially rectangular in plan, and consists of a bottom 1, a pair of side walls 2, 3, and a pair of end walls 4, 5. The side and end walls are disposed at an outward inclination with respect to the bottom 85 1, whereby the container or body portion is of flaring contour.

The bottom 1 is upset at the longitudinal center thereof to provide a pair of lengthwise extending spaced ribs 6, 7, and between 90 the ribs the bottom 1, is further upset to form centrally thereof, a circular rib 8 and the material of the bottom 1 surrounded by the rib 8 can be stamped or otherwise provided with the name of the manufacturer 95 or any suitable advertising indicia.

The ribs 6, 7 and 8 reinforce the bottom 1, thereby increasing the rigidity thereof.

Each of the end walls 4, 5, is arcuate in 100 contour and centrally thereof at the top is formed with a resilient curved extension 9 constituting a latching element employed

- for detachably connecting the cover or lid in closure position with respect to the container or body portion. The latching element 9 is extended laterally in a curvilinear manner from the top edge of an end well and then bent inwardly in a curvilinear manner, and whereby the latching element in cross section is substantially semi-oval in contour.
- 10 At the point of joinder of the side walls 2, 3, with the end walls 4, 5, or rather at the corners of the container or body portion, the side and end walls are corrugated, as at 10 and with the corrugations extending from the bottom 1 to the upper edges of the side and end walls and further with the corrugations extending towards each other at an inclination from the outer towards the inner end of the walls, and by setting up the corrugations in the side and end walls the corners of the container or body portion are reinforced.
- 15 The cover or lid is of greater length than the length of the container or body portion, and comprises an intermediate portion 11 and a pair of end portions 12, 13. The intermediate portion 11 is angle-shape in cross section and is so set up that it will depend down from its longitudinal center outwardly, and said intermediate portion 11 is of greater width than the width of the container or body portion.
- 20 The intermediate portion, at each side thereof, is provided with a set of spaced transversely extending oval-shape openings 14, which enable the fowls to have access to the feed within the container or body portion, and the material of the intermediate portion 11 which surrounds each opening 14, is upset to provide a reinforcing rib 15 which constitute a continuous curved wall for each opening and prevent the animal from injuring its mouth or head when feeding. The material of the intermediate portion 11, between the inner openings of each set, is upset as at 16, to form reinforcing ribs which terminate in the ribs 15 which surround the inner openings of the set. The ribs 16 are disposed longitudinally with respect to the intermediate portion 11. Each of the ribs 15 which surrounds the outer openings of a set, has extending from the outer side thereof a rib 17, formed by upsetting the material of the intermediate portion 11. The ribs 17 are arranged in alignment with the ribs 16.
- 25 The end portions 12 and 13 extend downwardly from the termini of the intermediate portion 11 so as to overlap the ends of the container or body portion, and the said end portions 12 and 13 project outwardly from the end of the container or body portion. At the point of joinder of the intermediate 11 with the end portions 12, 13, the cover or lid is provided with

sets of oppositely extending corrugations, as indicated at 18, 19, for the purpose of reinforcing the ends of the cover, and the said corrugations are disposed at an inclination and the corrugations of each set merge into each other at the longitudinal center of the cover or lid.

30 Each of the end portions 12, 13, centrally thereof, is formed with an arcuate shaped slot 20 and through the slots 20 are adapted to extend the latching elements 9, in a manner as shown in Figures 2 and 4. For the purpose of detachably connecting the cover or lid with the body portion—

35 The cover or lid is formed with a vertically disposed continuous flange 21, and the corrugations 18 and 19 are continued to extend through said flange.

40 Although the feed openings 14 are illustrated as of oval contour, yet it is to be understood that said openings can be set up of any suitable contour and that the openings of each set can be of any suitable number desired.

45 The setting up of the container or body portion, or as sometimes termed a pan, in the manner as shown, provides for the nesting of a series thereof when shipping, and the contour of the cover or lid is also provided for the nesting of a series thereof when shipping. Further, the reinforcing of the corners of the container, as well as the ends of the cover, reduces the bending inwardly or outwardly of the container or cover at such points to a minimum when handling, under such conditions the life of the container or cover is increased. As the cover is detachably connected with the container by the latching elements 9, the cover cannot be accidentally disconnected from the container, thereby preventing the fowls from using the trough otherwise than through the openings 14.

50 Although the preferred embodiment of a feed trough in accordance with this invention, is as illustrated and described, yet it is to be understood that changes in the details of construction can be had which will fall within the light of the invention as claimed.

55 What we claim is:—

1. A feed trough comprising a shallow container including a pair of end walls each having integral therewith, centrally thereof, and projecting outwardly from its top edge a resilient latching element offset intermediate its ends, and a cover formed with a pair of inclined depending end portions each provided with a transverse slot for the passage of a latching element and with the outer side edges of the slots engaging under the offset portions of the latching elements for detachably securing the cover to the container.
- 60 2. A feed trough comprising an open top

container, a resilient latching element projecting outwardly from each end thereof, each of said elements offset intermediate its ends, and a cover provided near each end with a slot for the passage of a latching element, the edges of said slots engaging under the offset portions of said elements

for detachably securing the cover upon the top of the container.

In testimony whereof, we affix our signatures hereto.

DANIEL E. SPEICHER.
ELROY C. FAUST.
